Primary Examiner — Susan Bennett Hattan*Assistant Examiner* — Vy Koenig**CLAIM**

We claim the ornamental design for a bench, as shown and described.

DESCRIPTION

FIG. 1 is a front perspective view of a bench, according to one embodiment;

FIG. 2 is a front view of a bench of FIG. 1, the rear view is a mirror image of the front view of FIG. 2;

FIG. 3 is a right side view of a bench of FIG. 1, the left side view is a mirror image of the right side view of FIG. 3;

FIG. 4 is a top view of a bench of FIG. 1;

FIG. 5 is a bottom view of a bench of FIG. 1;

FIG. 6 is a front perspective view of a bench according to a second embodiment;

FIG. 7 is a front view of a bench of FIG. 6, the rear view is a mirror image of the front view of FIG. 7;

FIG. 8 is a right side view of a bench of FIG. 6, the left side view is a mirror image of the right side view of FIG. 8;

FIG. 9 is a top view of a bench of FIG. 6; and,

FIG. 10 is a bottom view of a bench of FIG. 6.

The broken lines are for purposes of illustrating environmental structure and form no part of the claimed design.
